MECHANICAL PENCIL

Keith T. Bleuer, Oak Park, Ill.

Application September 15, 1945, Serial No. 616,497

19 Claims. (Cl. 120—18)

1

My invention relates to mechanical pencils and more particularly to such pencils of the magazine type. By a mechanical pencil I mean a pencil which is so constructed that, by suitable manipulation thereof by the user, lengths of lead or other writing material in stick form are propelled from the tip of the pencil, and by a magazine type mechanical pencil I mean a pencil having a magazine for sticks of writing material or leads and which functions on repeated operations of the lead propelling means of the pencil to successively feed leads out of the tip of the pencil from the magazine without the necessity of manually refilling the pencil in any way successively for each lead to be propelled through the tip of the pencil.

It is an object of my invention to provide an improved lead propelling mechanism which may be used in a mechanical magazine pencil. More particularly it is an object to provide such an improved mechanism that includes a lead propeller which abuts the ends of the leads in a pencil to push the leads toward the tip of the pencil whereby there can be no slippage between the propeller and the leads. It is contemplated that the lead propeller shall preferably function to push a lead a predetermined distance toward the tip of the pencil and under continued operation of the manual operating means of the pencil shall move out of the way for propelling a stick of lead and back to its original position for propelling another stick of lead toward the tip of the pencil.

It is a further object of my invention to provide two such lead propellers in a mechanical pencil with the propellers and the mechanism for moving them being so arranged that one of the lead propellers is moved in one direction to propel a lead toward the tip of the pencil while the other propeller is moved in the opposite direction back toward its original position and out of position for acting on a stick of lead. It is contemplated that with such an arrangement of two propellers, there may be little lost movement of the manual operating means of the pencil which does not cause a corresponding movement of a stick of lead out of the tip of the pencil, as compared to a pencil construction having only one such propeller and in which there would be a lost movement of the manual operating means of the pencil corresponding to the movement of the propeller back to its original starting position from its position at which it is moved out of contact with a lead for propelling it and after it has propelled the stick of lead the predetermined distance.

2

It is a more specific object of my invention to provide such a mechanical pencil in which a helical element is provided for moving one of the propeller elements in one direction and in which another helical element is provided for providing a corresponding movement of the other propeller element in the opposite direction. It is contemplated that the helical elements shall preferably form tracks for the propeller elements and that the propeller elements may be caused to move in the tracks by a manually rotatable element slidably carrying the propeller elements.

It is another object of my invention to provide, in connection with such a magazine pencil having a propeller element movable forwardly for propelling a stick of lead and back to its original position after having propelled the lead a predetermined distance, means for providing a gap between consecutive leads from the magazine at the

point in the lead channel at which the propeller element enters to allow the entrance of the propeller element into the lead channel. It is an object in connection with a mechanical pencil having two propeller elements as above described to provide means for preventing a feed of leads from the magazine as each of the lead propellers completes its return movement and just prior to the entrance of the propeller into the lead channel into its starting position to provide such a gap between consecutive leads to allow the lead propeller to enter the channel. It is contemplated that spring means adapted to act on the leads as they feed from the magazine and actuated by the propellers as they return to their starting positions may be used for carrying out this object.

It is also an object of the invention to provide an improved method for propelling leads in a mechanical pencil, such method being carried out by the manner of functioning of the propeller mechanism as above described, but the method itself, it being understood, being independent of any particular construction of mechanical pencil mechanism.

45 My invention consists of the novel methods, constructions, arrangements and devices to be hereinafter described and claimed for carrying out the above stated objects and such other objects as will appear from the following description of a certain preferred embodiment of mechanical pencil illustrated in the accompanying drawing, wherein:

Fig. 1 is a longitudinal sectional view of a mechanical pencil embodying the principles of the invention; and

Fig. 2 is a fragmentary side view of the man-

ually operated element of the pencil carrying the propeller elements as seen from the left of Fig. 1.

Figs. 3, 4, 5 and 6 are sectional views taken respectively on lines 3-3, 4-4, 5-5, and 6-6 in the directions indicated.

The same characters of reference designate the same parts in the several views of the drawing.

Referring now to the drawing, it will be observed that the illustrated pencil comprises an outer casing 10 which is preferably made of Bakelite or any suitable plastic. The outer surface of the casing may be flat sided, the illustrated casing 10 being provided with twelve flat sides 11 as shown, to facilitate the holding of the pencil by the user. Tubular elements 12 and 13 are provided within the casing 10. The element 12 is disposed in the forward end of the pencil, that is, the end adjacent the writing point hereafter to be described, and the element 13 is disposed in the rear end of the pencil and the elements 12 and 13 abut in the central region of the pencil as shown. The tubular element 12 is provided with a helical slot 14 therein which is adapted to function as a track for a lead propelling element, as will be described hereinafter. The tubular element 13 has considerably less thickness than the element 12 and is provided to act as a bearing sleeve for receiving certain rotatable parts therein hereinafter to be described. The tubular elements 12 and 13 may be cast within the casing 10 when the casing is made to fix the elements therein or the elements may be fixed within the casing by any other suitable method, such as by providing the tubular elements with a drive fit in the casing and driving them in the casing after the casing has previously been cast.

A tip 15 is provided for the pencil. The tip has a sleeve-like portion 16 which fits over the forward end 17 of the tubular element 12, and the tip is fixed with respect to the tubular element 12 and thereby with respect to the casing 10 by being threaded on the forward end 17 of the tubular element 12. The tip is provided with a central cylindrical cavity 18 therein extending longitudinally of the tip, and this cavity is adapted to function as a channel to receive the sticks of writing material for which the pencil is intended to be used. It will be understood that these sticks may be of commonly used writing lead or may be of any other writing material, and for the purpose of conciseness the sticks will be referred to as sticks of lead hereinafter. The tip 15 is provided at its forward end with a plurality of slits 19 which form a corresponding number of fingers 20. The fingers 20 are made to act as spring fingers which grip a lead in the channel 18 between them so as to hold the lead firmly at the writing point of the pencil.

The tip 15 has a tubular portion 21 which extends inwardly into the pencil on the axial center of the pencil and is concentric with the tubular element 12. The internal cavity in the tubular portion 21 constitutes a part of the channel 18 for sticks of lead as is apparent from an inspection of the drawing. The tubular portion 21 is provided with a helical slot 22 therein, and this slot like the slot 14 in the element 12, is adapted to constitute a track for lead propeller elements hereinafter to be described. It will be noted that the helical slots 14 and 22 are of opposite hand; looking from the rear end of the pencil, the slot 14 is left-handed and the slot 22 is right-handed.

A cylindrical element 23 is rotatably disposed within the sleeve 13. The element 23 has a portion 24 protruding from the sleeve 13 and casing

10, and this portion is adapted to be used for rotating the element 23 with respect to the casing 10 of the pencil for causing additional lead to be protruded from the tip of the pencil as will be hereinafter more fully described. The element 23 is provided with an inwardly tapering portion 25 and a tubular portion 26, connected together as shown. The element 23 forms a magazine 27 for sticks of lead, and the tapering portion 25 forms the bottom of the magazine. The inner cavity in the tubular portion 26 forms a part of the channel 18 for sticks of lead which, as is apparent from an inspection of the drawing, extends from the magazine 27 to the pencil tip 15. It will be noted that the tubular element 12 has an inwardly chamfered rear end 28, and the tapering portion 25 abuts against and is rotatably disposed in this end of the tubular element 12. The rear end of the element 12 thus forms a bearing for the rotatable element 23 and prevents movement thereof forwardly of the pencil. The tubular portion 26 is tapered on its forward end and the tubular slotted portion 21 is inwardly chamfered on its rear end, and the tubular portions 26 and 21 fit together as at 29. The magazine element 23 is rotatable while the tubular portion 21 is stationary with respect to the casing 10, so it is necessary to provide this break in the lead channel at 29; however, the beveled ends of the tubular portions 26 and 21 at 29 function to keep the tubular portions 26 and 21, and thus the parts of the lead channel 18 formed thereby, coaxially disposed with respect to each other.

A cap 30 carrying a rubber eraser 31 therein is disposed in the rear end of the manually rotatable tubular element 23. The tubular element 23 is provided with stops 32 on its inner surface with which the cap 30 is adapted to abut. The cap is frictionally held in the element 23, but may be removed therefrom when desired, and the cap may be reversed and again put into the element 23 so that the rubber eraser protrudes from the rear end of the element 23 and may be used for erasing. The stops 32 prevent the cap element 30 from moving any farther forwardly in the magazine 27 than in the position in which the cap is shown, whether the cap is in its position in which it is shown or is in reversed position for erasing.

A cylindrical element 33 is disposed within the slotted tubular element 12 and is eccentrically disposed with respect to the element 12 as shown. The element 33 is made up of two parts 34 and 35 which are spaced from each other by slots 36 and 37 extending longitudinally of the pencil and by slots 38 and 39 at the ends of the slots 36 and 37 and extending transversely of the pencil. The slots are all in communication with each other so as to provide a track in the element 33 which extends forwardly of the element 33 (in the slot 37), thence transversely of the element 33 for 180 degrees (in the slot 39), thence rearwardly of the element 33 (in the slot 36) and thence transversely of the element 33 for 180 degrees (in the slot 38). The element 33 is fixed with respect to the manually rotatable element 23 so as to be rotatable therewith. The part 35 is fixed to the element 23 at the rear end of the part by any suitable means as by welding as at 40, and the other part 34 is fixed with respect to the rotatable element 23 by means of a longitudinally extending bridging element 41 and a washer-like element 42. The element 41 is welded to the rear end of the part 35 as at 43 to fix the element 41 to the part 35 and to the rotatable element 23. Both the element 41 and the part 34 at their for-

ward ends extend through the washer-like element 42, and the elements 41 and 42 are welded together at 44, and the element 42 and part 34 are welded together at 45. The parts 34 and 35 being separated by the slots 36, 37, 38 and 39, have no direct connection between them; however, the bridging element 41 and the washer-like element 42 connect the two parts together so the parts together form the element 33 which is rotatable with the manually rotatable element 23. It will be noted that for the major part of its length, the bridging element 41 is in contact with the inner surface of the slotted element 12 and is spaced from the element 33, for purposes which will hereinafter be described.

The pencil includes two lead propeller elements 46 and 47, and each propeller element comprises a pin 48 and a semi-cylindrical part 49. It will be noted that the pin extends through the cylindrical part and extends both inside and outside of the part, and the pin is fixed within the cylindrical part by any suitable means as by welding. The propeller elements fit on the eccentrically disposed cylindrical element 33, and the pins 48 move in the slots 36, 37, 38 and 39 of the cylindrical element which form a track in the element as above described. The pins 48 are also adapted to fit in and move in the slots 14 and 22 of the cylindrical element 12 and cylindrical portion 21 which are fixed with respect to the casing 10 of the pencil. As will be noted by reference to the drawing, the lead propeller element 47 in its illustrated position in the slot 36 has its pin 48 also in the slot 14, and the other propeller element 46 which is shown in the slot 37 has its pin 48 also in the slot 22 of the centrally disposed tubular portion 21, and the latter pin extends into the central cavity of the tubular portion 21 which forms part of the channel 18 for the lead. As the propeller elements 46 and 47 move within the slot 37 as will be hereinafter described, the ends of their pins 48 contact the inner surface of the bridging element 41, and this element is provided with a cam portion 50 which is adapted to contact the ends of the pins as the corresponding propeller elements move in the transversely extending slot 39.

A spring 51 is provided within the part 35 of the eccentrically disposed propeller carrier 33. The spring has a portion 52 extending through a slot 53 in the part 35 (see Fig. 6) and a tang portion 54 extending through a slot 55 provided in the tubular portion 26. The spring is attached to the part 35 by any suitable means such as rivets 56 (see Fig. 1). The cylindrical parts 49 of the propeller elements 41 are adapted to make contact with and move over the spring portion 52 and press the tang portion 54 of the spring through the slot 55 in the tubular portion 26 for contacting and gripping a lead within the tubular portion 26 and preventing the lead from dropping forwardly in the lead channel within the tubular portion. The spring 51 is preferably provided with a chamfered portion 57 at its forward edge so that the cylindrical parts 49 may readily come into position to press the tang 54 against a lead in the channel 18 in the tubular portion 26, as will be hereinafter more fully described. A guide 58 is disposed about the part 35 and is fixed thereto as by welding at 59. The guide is adapted to receive the cylindrical parts 49 of the lead propeller elements 46 and 47 when the latter are in position to act on the spring, and the guide acts to hold the cylindrical parts 49 in contact with

the tubular part 33 and in position to press on the spring 51.

In the operation of the illustrated embodiment of the invention, element 23 by means of its end portion 24 protruding from the casing 10 is rotated in the clockwise direction, as seen in Figs. 3 to 5, to cause leads to be fed from the tip 15 of the pencil. It is intended that the pencil shall be held in a vertical or in an approximately vertical position, as gravity is relied on to cause the leads to feed forwardly of the pencil from the magazine 27; such a vertical position for the pencil is of course the natural position for holding a pencil. It is also intended that leads only of the same standard size be used, as will be described. Let it be assumed that the propeller element 47 is in a position forwardly of its position in which it is shown in the drawing so that its pin 48 is at the point 14a in the slot 14 in the tubular element 12. The propeller element 46 is then in a position rearwardly of its position in which it is shown so that its pin 48 is at the point 22a in the slot 22 in the tubular portion 21. As will be readily understood by reference to the drawing, the pin 48 of the propeller element 47 which is in the slot of the outer tubular element 12 is in inoperative position with respect to lead in the channel 18, as it does not extend into the channel. The pin 48 of the propeller element 46 on the other hand extends through the helical slot 22 in the tubular portion 21 and into the lead channel 18, and this propeller element is thus in operative position in which it is adapted to propel a stick of lead within the channel 18. The helical slot 14 in the outer tubular element 12 thus constitutes an inoperative track for the propeller elements 46 and 47, and the slot 22 in the tubular portion 21 constitutes an operative track for the propeller elements.

Assuming then that the propeller elements 46 and 47 are in their changed positions with the pins 48 of the elements being respectively at the points 22a and 14a in the operative and inoperative tracks, a rotation of the element 23, and of the element 33 attached thereto in the clockwise direction as seen in Figs. 3 to 5 will cause a corresponding rotation of the propeller elements 46 and 47. The motion is transmitted to the propeller elements through the cylindrical element 33 by means of the edges of the slots 36 and 37 through which the pins 48 of the propeller elements 47 and 46 respectively extend. The pin 48 of the propeller element 47 due to this rotation of this element travels in the slot 14 rearwardly of the point 14a in the slot, and the propeller element 47 as a whole has this rearward movement moving over the propeller carrier element 33 with the pin 48 also moving in the slot 36. The pin 48 of the propeller element 46 moves in the forward direction through the slot 22 from the point 22a in the slot, and the propeller element as a whole has this movement moving over the propeller carrier element 33 with its pin 48 moving also in the slot 37. The pin of the propeller element 47 is out of the channel 18 for the leads but the pin of the propeller element 46 is in the channel and abuts the end 60 of a stick of lead 61 in the channel. The lead is thus moved toward the tip 20 of the pencil by movement of the propeller element 46, and the lead actually extending from the tip 15 is moved out of the tip so as to present a greater length of lead at the end of the tip for writing purposes. This movement in opposite directions of the propeller elements 46 and 47 is due to the fact that the

helical slots 14 and 22 are of opposite hand, as will be observed from the drawing. The helical slots furthermore are coextensive and have the same number of turns so that a rotation of the element 23 gives the same movement along the length of the pencil to both the propeller elements 46 and 47.

After three turns of the rotatable element 23, the propeller element 47 is in the position in which it is illustrated with the pin 48 of the element 47 having moved from the point 14a in the slot 14 three turns rearwardly in the slot to the end 14b thereof and to the rear end of the slot 36 which is in communication with the transverse slot 38 in the cylindrical element 33. The propeller element 46 is moved by such rotation of the element 23 three turns forwardly in the slot 22 to its illustrated position in which its pin 48 is at the end 22b of the slot 22 and in which the pin is at the forward end of the slot 37 that is in communication with the transverse slot 39 in the element 33. Such movement of the propeller element 46 of course causes a corresponding expulsion of lead from the tip 15, as will be understood.

After the propeller elements 47 and 46 have reached their illustrated positions, a further one-half turn of the manually rotatable element 23 will move the propeller element 47 inwardly to bring its pin 48 into the helical slot 22 at the end 22c thereof (see Fig. 5) and will move the propeller element 46 outwardly to bring its pin 48 into the helical slot 14 at the end 14c thereof (see Fig. 3). Due to the fact that the propeller element 47 in its illustrated position is at the end 14b of the slot 14, such a rotation of the element 23 causes movement of the pin 48 of the propeller element 47 in the transverse slot 38 in the rotatable element 33, although, as will be understood, it is actually the parts 34 and 35 defining the slot that rotate, rather than the propeller element 47. The semi-cylindrical part 49 of the element 47 is within the guide 58, and such rotation of the element 33 causes the part 49 to move over the surface of the element 33 within the guide while the pin 48 of the propeller element 47 is moving in the slot 38. Since the element 33 is eccentrically located with respect to the center of the pencil, this rotation of the element causes the propeller element to move toward the center of the pencil until the pin 48 of the propeller element enters the helical slot 22 and the lead channel 18. The propeller element 47 cannot rotate again until its pin 48 is completely out of the slot 14 and the element 33 has made a complete half turn to bring the slot 37 into position so that the pin 48 of the propeller element 47 can enter the slot. The propeller element 47 is then in position to begin its travel forwardly of the pencil to propel a lead in the channel. A gap between the rear end 62 of a lead 63 and the forward end 64 of another lead 65 in the channel is automatically provided by the action of the spring 51 to allow the pin 48 of the propeller element 47 to enter the channel, as will be hereinafter described.

This half turn of the element 33 effective for moving the pin 48 of the propeller element 47 into the lead channel 18 is also effective to move the pin 48 of the propeller element 46 into the slot 14 at its end 14c and out of the lead channel with a corresponding outward movement of the propeller element 46 as a whole. The pin of the element 46 travels in the transverse slot 39 of the element 33, and its semi-cylindrical

part 49 moves over the surface of the element 33 similar to the manner of movement of the propeller element 47 so as to move the propeller element 46 outwardly. The cam 50 contacts the end of the pin 48 of the propeller element 46 and functions to hold the propeller element in contact with the outer surface of the element 33.

The propeller element 47 is now disposed inwardly of its illustrated position with its pin 48 in the slot 22, and the propeller element 46 is outwardly disposed of its illustrated position with its pin 48 in the slot 14. Further rotation of the rotatable element 23 will cause the propeller element 47 to move forwardly of the pencil with its pin 48 being disposed in the slots 22 and 37, and the propeller element will abut the end 62 of the stick of lead 63 and will move the lead forwardly in the pencil so that a further length of lead will be propelled from the tip 15. This same rotation of the rotatable element 23 will cause the propeller element 46 to have a corresponding movement rearwardly of the pencil with its pin 48 being in the slots 36 and 14. The propeller element 47 will eventually reach the position that propeller element 46 occupies in the drawing, and the propeller element 46 will eventually reach the position that propeller element 47 occupies in the drawing, and further movement of the rotatable element 23 will cause the propeller elements each to take the same path back to its illustrated position that the other propeller element has just been described as taking. It will thus be apparent that each propeller element moves forwardly of the pencil in the slot 22 propelling the lead in the channel 18, then moves outwardly into the slot 14, then moves rearwardly of the pencil in the slot 14 and then moves inwardly again into the slot 22 and channel 18. The two propeller elements 46 and 47 are at opposite ends of the cycle; that is, one of the propeller elements is moving into the lead channel 18 while the other is moving out of it, and one propeller element is moving rearwardly of the pencil while the other propeller element is moving forwardly of the pencil.

As has been mentioned, the spring 51 operates to provide a gap between two consecutive leads at the point where the propeller elements 46 and 47 enter the lead channel 18, in order that the propeller elements may enter the channel without interference. The pencil is normally held vertically or substantially so, and this is relied on to cause the leads to feed forwardly of the pencil and to cause a lead between the points in the lead channel 18 at which the propeller elements enter and leave the lead channel, such as the lead 63, to stay in contact with the pin 48 of the foremost propeller element, which is the propeller element 46 in the illustration, as long as the propeller element is in the channel, and to move into contact with the stick of lead immediately ahead, which is the lead 61 in the illustration, when the propeller element moves out of the lead channel and into the slot 14 of the outer tubular element 12. The spring 51 operates specifically to clamp a lead and hold it from further forward movement in the lead channel 18 when one of the propeller elements is completing its rearward movement and as it moves again into the lead channel. The propeller element 47, for example, just before it reaches its illustrated position has its semi-cylindrical part 49 enter the guide 58 and contact the chamfered end 57 of the spring 51. Further movement rearwardly of the propeller

element causes the spring to be sprung to bring its tang portion 54 into contact with the lead which is beneath the tang portion. In the drawing, this lead is the lead 65. As the propeller element moves still farther rearwardly, it continues to bear on the spring 51 to hold the lead 65 from further forward movement, as will be apparent.

During this time, the other propeller element 46 at the forward end of the pencil continues to move and thereby allows the lead 63 to move forwardly of the pencil, and when the propeller elements have reached their illustrated positions, there is a substantial gap between the leads 65 and 63 so that the propeller element 47 has no interference in entering the lead channel 18.

It will be understood that the spring 51 operates in the same manner for both of the propeller elements to provide this gap, and that although the movement of the propeller elements has been described as continuous, actually the manually rotatable element 23 is given only small movements at a time just sufficient to propel a sufficient length of lead from the tip 15 to provide a writing point. When one propeller element moves into the lead channel 18 and the other propeller element moves out, there is some lost motion of the rotatable element 23 which does not cause a corresponding increase in the writing length of lead at the tip 15; however, the rotatable element 23 is simply continued to be turned until the lead is again propelled from the tip 15 and a sufficient length of writing point is obtained. It is contemplated that lead of a standard length, such as the illustrated length of the lead 63 in relation to the other parts of the pencil, only be used with the pencil in order that the spring 51 will function to provide the proper gap between leads at the point where the propeller elements enter the channel 18. It will be noted that the portion 52 of the spring is acted on by the semi-cylindrical portions 49 while the propeller elements 46 and 47 travel in the transverse slot 38, and the spring thus is operative as the pins 48 actually move into the helical slot 22.

The parts of the pencil are preferably made of metal, with the exception of the outer casing 10 which may be of plastic, and, of course, with exception also of the eraser 31. The pencil is assembled by first casting the tubular elements 12 and 13 within the plastic casing 10. The parts 23, 41, and 35 are assembled and welded together (without the parts 42 and 34), and the propeller element 47 is put into its illustrated position at the end 4b of the slot 14. The assembly of the parts 23, 41, and 35 is then put into the casing 10 from the rear to bring these parts into their illustrated positions with the tapered portion 25 in contact with the chamfered end 23 of the tubular element 12. The propeller element 46 is then put within the casing with the end of its pin 48 in contact with the bridging element 41, and the part 34 is then put into the casing 10 from the front end of the casing into its proper place. The washer 42 is then put over the forward ends of the parts 41 and 34 and in contact with the forward end of the tubular element 12, and the parts 41 and 34 are welded to the washer at 44 and 45 respectively. The tip 15 together with the tubular portion 21 are then ready to be put into place, but the propeller element 46 is first moved rearwardly of the pencil a distance equal to a few turns of the slot 22 in the tubular portion 21. The tubular por-

tion 21 is then inserted into the pencil through the central opening in the end of the part 34 and when the sleeve-like portion 16 is substantially abutting the washer 42, the tip 15 and tubular portion 21 are moved inwardly, so as to bring the pin 48 of the propeller element 46 into the slot 22. The tip 15 is then screwed onto the threaded portion 17 of the tubular element 12, and this rotation of the tip and the tubular portion 21 causes the propeller element 46 to move in the slot 22 and into its illustrated position. The thread 17 is made right handed for this purpose, namely, to bring the propeller element 46 forwardly as the tip is threaded on the tubular element 12. It will be understood that the propeller element 46 is moved back into the pencil just far enough prior to its being engaged in the slot 22 and prior to the rotation of the tip 15 in threading it into place so that this rotation is just enough to bring the propeller element into its illustrated position. The pencil is now completely assembled, and lead may be inserted into the magazine 27, and the element 23 may be rotated to feed the lead through the pencil.

My improved pencil advantageously provides positive propulsion of leads through the pencil by means of the propeller elements which engage the sticks of lead at their ends. The pencil comprises two of the propeller elements one of which is operative while the other is inoperative so that an excessive manual movement is not required in order to cause propulsion of consecutive sticks of lead through the pencil. The pencil furthermore includes a compact mechanical arrangement comprising the two opposite handed slots 14 and 22 and the eccentrically disposed propeller carrier element 33 for moving the two propeller elements in opposite directions in the pencil and for moving the propeller elements into and out of their operative and inoperative tracks.

I wish it to be understood that I do not intend to limit my invention to the specific constructions and arrangements shown and described except only insofar as the claims may be so limited, as it will be apparent to those skilled in the art that changes may be made without departing from the invention. In particular, I wish it to be understood that I do not intend to limit the invention to helical members (12 and 21) for propelling the sticks of lead, unless the claims are so limited.

I claim:

1. In a mechanical pencil, the combination of means defining a channel for sticks of writing material, a pair of propeller elements for abutting sticks of writing material in said channel at the ends of the sticks for propelling the sticks through the channel, and manually operated means for moving each of said propeller elements through said channel for a predetermined distance and then out of the channel and then back said predetermined distance and again into the channel into its starting position, said two propeller elements being so operated with respect to each other that one of them is moving in one direction and is in said channel to propel a stick of writing material therein while the other propeller element is moving in the opposite direction and is out of the channel.

2. In a mechanical pencil, the combination of a tubular element defining a channel for sticks of writing material, a propeller element for abutting sticks of writing material in said channel at the ends of the sticks for propelling the sticks

through the channel, said tubular element having a helical slot therein defining a track for said propeller element, a tubular element concentric with said first named tubular element and having a helical slot therein also defining a track for said propeller element, manually operated means for causing said propeller element to move in said tracks, the track in said first named tubular element causing movement of said propeller element while the propeller element is in said channel to propel a stick of writing material in the channel and the track in the other tubular element causing movement of the propeller element in the opposite direction while the propeller element is out of the channel, and means for moving said propeller element from one of said tracks to the other after it has travelled a predetermined distance in said one track.

3. In a mechanical pencil, the combination of means defining a channel for sticks of writing material, a pair of propelling elements for abutting sticks of writing material in said channel at the ends of the sticks for propelling the sticks through the channel, and manually operated means for moving said propeller elements, one of said propeller elements while in position for abutting a stick of writing material in said channel being given a movement in one direction to propel the stick through the channel and the other propeller element being given a movement in the opposite direction while out of position for propelling a stick of writing material in said channel by an operation of said manual means.

4. In a mechanical pencil, the combination of means defining a channel for sticks of writing material, a pair of propeller elements for abutting sticks of writing material in said channel at the ends of the sticks for propelling the sticks through the channel, means defining a track for one of said propeller elements in which the propeller element is out of position for propelling a stick of writing material in said channel, means defining a track for the other of said propeller elements in which the propeller element is in position to propel a stick of writing material in said channel, and manually operated means for moving said propeller elements, the propeller element in said first named track being given a movement for propelling a stick of writing material through said channel and the propeller element in the other track being given a movement in the opposite direction by an operation of said manual means.

5. In a mechanical pencil, the combination of means defining a channel for sticks of writing material, a pair of propeller elements for abutting sticks of writing material in said channel at the ends of the sticks for propelling the sticks through the channel, means defining operative and inoperative tracks for said propeller elements in which the propeller elements are respectively in position for propelling a stick of writing material in said channel or are out of position for propelling sticks of writing material in said channel, one of said propeller elements being in an operative track while the other propeller element is in an inoperative track, manually operated means for moving said propeller elements, the propeller element in an operative track being given a movement to propel a stick of writing material and the other propeller element being given a movement in the opposite direction by an operation of said manual means, and means for moving one of said propeller elements from an operative track to an inoperative track and for moving the other propeller element from an inoperative track to an operative track by an operation of said manual means after the propeller elements have travelled predetermined distances in the tracks in which they were originally.

inoperative track to an operative track by an operation of said manual means after the propeller elements have travelled predetermined distances in the tracks in which they were originally.

6. In a mechanical pencil, the combination of means defining a channel for sticks of writing material, a pair of propeller elements for abutting sticks of writing material in said channel at the ends of the sticks for propelling the sticks through the channel, helical elements defining operative and inoperative tracks for said propeller elements in which the propeller elements are respectively in position for propelling a stick of writing material in said channel or are out of position for propelling sticks of writing material in said channel, one of said propeller elements being in an operative track while the other propeller element is in an inoperative track, rotatable means adapted to be operated manually for moving said propeller elements, the propeller element in an operative track being given a movement to propel a stick of writing material and the other propeller element being given a movement in the opposite direction by an operation of said manual means, and means for moving one of said propeller elements from an operative track to an inoperative track and for moving the other propeller element from an inoperative track to an operative track by an operation of said manual means after the propeller elements have travelled predetermined distances in the tracks in which they were originally.

7. In a mechanical pencil, the combination of means defining a channel for sticks of writing material, a pair of propeller elements for abutting sticks of writing material in said channel at the ends of the sticks for propelling the sticks through the channel, means defining an operative track in which both of said propeller elements may travel and in which the propeller elements are in position for propelling a stick of writing material in said channel, means defining an inoperative track in which both of said propeller elements may travel and in which the propeller elements are out of position for propelling a stick of writing material in said channel, one of said propeller elements being adapted to be in one of said tracks while the other propeller element is in the other track, manually operated means for moving said propeller elements, the propeller element in the operative track being given a movement to propel a stick of writing and the other propeller element being given a movement in the opposite direction by an operation of said manual means, and means for moving the propeller element in said operative track to said inoperative track and for moving the propeller element in said inoperative track to said operative track by an operation of said manual means after the propeller elements have travelled predetermined distances in the tracks in which they were originally.

8. In a mechanical pencil, the combination of means defining a channel for sticks of writing material, a pair of propeller elements for abutting sticks of writing material in said channel at the ends of the sticks for propelling the sticks through the channel, a helical element defining an operative helical track in which both of said propeller elements may travel and in which the propeller elements are in position for propelling sticks of writing material in said channel, a helical element defining an inoperative helical track in which both of said propeller elements may travel and in which the propeller elements are

out of position for propelling sticks of writing material in said channel, one of said propeller elements being adapted to be in one of said tracks while the other propeller element is in the other track, manually rotatable means for causing relative rotation between said propeller elements and said helical elements whereby the propeller elements travel in said tracks, the propeller element in the operative track being given a movement to propel a stick of writing material and the other propeller element being given a movement in the opposite direction by an operation of said manual means, and means for moving the propeller element in said operative track to said inoperative track and for moving the propeller element in said inoperative track to said operative track by an operation of said manual means after the propeller elements have travelled predetermined distances in the tracks in which they were originally.

9. In a mechanical pencil, the combination of means defining a channel for sticks of writing material, a pair of propeller elements for abutting sticks of writing material in said channel at the ends of the sticks for propelling the sticks through the channel, said first named means defining an operative track in which both of said propeller elements may travel and in which the propeller elements are in position for propelling sticks of writing material in said channel, means defining an inoperative track in which both of said propeller elements may travel and in which the propeller elements are out of position for propelling sticks of writing material in said channel, one of said propeller elements being adapted to be in one of said tracks while the other propeller element is in the other track, manually operated means for moving said propeller elements, the propeller element in the operative track being given a movement to propel a stick of writing material and the other propeller element being given a movement in the opposite direction by an operation of said manual means, and means for moving the propeller element in said operative track to said inoperative track and for moving the propeller element in said inoperative track to said operative track by an operation of said manual means after the propeller elements have travelled predetermined distances in the tracks in which they were originally.

10. In a mechanical pencil, the combination of a central tubular element defining a channel for sticks of writing material, a pair of propeller elements for abutting sticks of writing material in said channel at the ends of the sticks for propelling the sticks through the channel, said tubular element having a slot therein and thereby forming an operative track in which both of said propeller elements may travel and in which the propeller elements are in position for propelling sticks of writing material in said channel, a tubular element concentric with said first named tubular element and having a slot therein to form an inoperative track for both of said propeller elements and in which the propeller elements are out of position for propelling sticks of writing material in said channel, one of said propeller elements being adapted to be in one of said tracks while the other propeller element is in the other track, manually operated means for moving said propeller elements, the propeller element in the operative track being given a movement to propel a stick of writing material and the other propeller element being given a movement in the opposite direction by an operation of said manual

means, and means for moving the propeller element in said operative track to said inoperative track and for moving the propeller element in said inoperative track to said operative track by an operation of said manual means after the propeller elements have travelled predetermined distances in the tracks in which they were originally.

11. In a mechanical pencil, the combination of a central tubular element defining a channel for sticks of writing material, a pair of propeller elements for abutting sticks of writing material in said channel at the ends of the sticks for propelling the sticks through the channel, said tubular element having a helical slot therein and thereby forming an operative track in which both of said propeller elements may travel and in which the propeller elements are in position for propelling sticks of writing material in said channel, a tubular element concentric with said first named tubular element and having a helical slot therein to thereby form an inoperative track for both of said propeller elements and in which the propeller elements are out of position for propelling sticks of writing material in said channel, one of said propeller elements being adapted to be in one of said tracks while the other propeller element is in the other track, manually rotatable means for giving relative rotation to said propeller elements with respect to said tubular elements whereby the propeller elements travel in the slots of the tubular elements, the propeller element in the operative track being given a movement to propel a stick of writing material and the other propeller element being given a movement in the opposite direction by a rotative movement of the manual means, and means for moving the propeller element in said operative track to said inoperative track and for moving the propeller element in said inoperative track to said operative track by a rotative movement of the manual means after the propeller elements have travelled predetermined distances in the tracks in which they were originally.
12. In a mechanical pencil, the combination of a central tubular element defining a channel for sticks of writing material, a pair of propeller elements for abutting sticks of writing material in said channel at the ends of the sticks for propelling the sticks through the channel, a tubular element concentric with said first named tubular element and spaced radially therefrom, said propeller elements being disposed between said tubular elements, said inner and outer tubular elements respectively defining operative and inoperative tracks for said propeller elements in which the propeller elements are respectively in position for propelling sticks of writing material in said channel or are out of position for propelling sticks of writing material in said channel, one of said propeller elements being in an operative track while the other propeller element is in an inoperative track, means disposed between said concentric tubular elements and adapted to have relative movement with respect thereto and acting on said propeller elements to move the same in said tracks, the propeller element in an operative track being given a movement to propel a stick of writing material and the other propeller element being given a movement in the opposite direction by a movement of said last named means relative to the tubular elements.
13. In a mechanical pencil, the combination of a central tubular element defining a channel for sticks of writing material, a pair of propeller ele-

ments for abutting sticks of writing material in said channel at the ends of the sticks for propelling the sticks through the channel, said tubular element having a slot therein and thereby forming an operative track in which both of said propeller elements may travel and in which the propeller elements are in position for propelling sticks of writing material in said channel, a tubular element concentric with said first named tubular element and having a slot therein to thereby form an inoperative track for both of said propeller elements in which the propeller elements are out of position for propelling sticks of writing material in said channel, one of said propeller elements being adapted to be in one of said tracks while the other propeller element is in the other track, manually movable means acting on said propeller elements to move the same and disposed between said tubular elements, the propeller element in the operative track being given a movement to propel a stick of writing material and the other propeller element being given a movement in the opposite direction by a movement of said manual means, and means for moving the propeller element in said operative track to said inoperative track and for moving the propeller element in said inoperative track to said operative track by a movement of said manual means after the propeller elements have travelled predetermined distances in the tracks in which they were originally.

14. In a mechanical pencil, the combination of a central tubular element defining a channel for sticks of writing material, a pair of propeller elements for abutting sticks of writing material in said channel at the ends of the sticks for propelling the sticks through the channel, said tubular element having a helical slot therein and thereby forming an operative track in which both of said propeller elements may travel and in which the propeller elements are in position for propelling sticks of writing material in said channel, a tubular element concentric with said first named tubular element and having a helical slot therein to thereby form an inoperative track in which both of said propeller elements may travel and in which the propeller elements are out of position for propelling sticks of writing material in said channel, one of said propeller elements being adapted to be in one of said tracks while the other propeller element is in the other track, a rotatable carrier element for said propeller elements disposed between said tubular elements and adapted to give relative movement to said propeller elements with respect to said tubular elements whereby the propeller elements travel in said helical slots, the propeller element in the operative track being given a movement by the track to propel a stick of writing material in said channel and the other propeller element being given a movement in the opposite direction by the other track on a movement of the manual means, and means for moving the propeller element in said operative track to said inoperative track and for moving the propeller element in said inoperative track to said operative track by a movement of said carrier element after the propeller elements have travelled predetermined distances in the tracks in which they were originally.

15. In a mechanical pencil, the combination of an inner tubular element defining a channel for sticks of writing material, a pair of propeller elements for abutting sticks of writing material in said channel at the ends of the sticks for propelling the sticks through the channel, an outer

tubular element concentric with said first named tubular element and spaced radially therefrom, said inner and outer tubular elements respectively defining operative and inoperative tracks for said propeller elements in which the propeller elements are respectively in position for propelling sticks of writing material in said channel or are out of position for propelling sticks of writing material in said channel, one of said propeller elements being in an operative track while the other propeller element is in an inoperative track, a tubular element disposed between said above named tubular elements and eccentrically with respect thereto whereby to have portions thereof adjacent both said inner and outer tubular elements, said eccentrically disposed tubular element being adapted to have movement relative to the other tubular elements and acting on said propeller elements to move the same in said tracks, the propeller element in an operative track being given a movement to propel a stick of writing material in said channel and the other propeller element being given a movement in the opposite direction by a movement of said eccentrically disposed tubular element relative to the other tubular elements, said eccentrically disposed tubular element on a rotation thereof relative to said first named tubular elements being adapted to move one of the propeller elements in an operative track to an inoperative track and to move the other propeller element from an inoperative track to an operative track after the propeller elements have travelled predetermined distances in the tracks in which they were originally.

16. In a mechanical pencil, the combination of an inner tubular element defining a channel for sticks of writing material, a pair of propeller elements for abutting sticks of writing material in said channel at the ends of the sticks for propelling the sticks through the channel, said tubular element having a helical slot therein and thereby forming an operative track in which both of said propeller elements may travel and in which the propeller elements are in position for propelling sticks of writing material in said channel, an outer tubular element concentric with said first named tubular element and having a helical slot therein to thereby form an inoperative track in which both of said propeller elements may travel and in which the propeller elements are out of position for propelling sticks of writing material in said channel, one of said propeller elements being adapted to be in one of said tracks while the other propeller element is in the other track, and a tubular carrier element for said propeller elements disposed between said inner and outer tubular elements and being eccentrically disposed with respect to said last named tubular elements whereby to have portions adjacent both inner and outer tubular elements, said carrier element being adapted to be manually rotated and moving said propeller elements in said slots while allowing movement of the propeller elements longitudinally of the pencil so that the propeller element in said operative track is moved to propel sticks of writing material in said channel and the other propeller element is moved in the opposite direction when the carrier element is rotated, said carrier element when rotated and when the propeller elements are at the ends of the tracks in which they are disposed functioning to move the propeller element in the operative track to the in-

operative track and the propeller element in the inoperative track to the operative track.

17. In a mechanical pencil, the combination of an inner tubular element defining a channel for sticks of writing material, a pair of propeller elements for abutting sticks of writing material at the ends of the sticks for propelling the sticks through the channel, said tubular element having a helical slot therein and thereby forming an operative track in which both of said propeller elements may travel and in which the propeller elements are in position for propelling sticks of writing material in said channel, a tubular element concentric with said first named tubular element and having a helical slot therein to thereby form an inoperative track in which both of said propeller elements may travel and in which the propeller elements are out of position for propelling sticks of writing material in said channel, one of said propeller elements being adapted to be in one of said tracks while the other propeller element is in the other track, and a tubular carrier element for said propeller elements disposed between said first named tubular elements and being eccentrically disposed with respect to the tubular elements, said carrier element having two opposite slots therein extending longitudinally thereof for receiving said propeller elements with the slots being so disposed that a propeller element in one of the slots is in said operative track and a propeller element in the other slot is in said inoperative track whereby the carrier element when rotated moves said propeller element in said operative track to propel a stick of writing material in said channel and moves the propeller element in the other track in the opposite direction, said carrier element having spaced transverse slots corresponding to ends of said helical slots and adapted to receive said propeller elements and connecting the longitudinal slots in the carrier element at opposite ends of these longitudinal slots whereby the carrier element when rotated and when the propeller elements have travelled to opposite ends of the longitudinal slots in the carrier element will move the propeller element in said operative track to the inoperative track and will move the other propeller element from said inoperative track to said operative track.

18. In a method for propelling sticks of writing material in a pencil which feed through a channel for the sticks, the steps which comprise, moving a propeller element in the channel for a prede-

termined distance to propel a stick of writing material therein, moving the propeller element out of the channel and back said predetermined distance, and then moving the propeller element again into said channel into its starting position at which it may act on another stick of writing material, and moving another propeller element in the same manner as the first named propeller element, each of said propeller elements being moved in said channel to propel a stick of writing material therein while the other propeller element is moved in the opposite direction without the channel.

19. In a method for propelling sticks of writing material in a pencil which feed from a magazine and thence through a channel, the steps which comprise, moving a propeller element abutting a stick of writing material in the channel for a predetermined distance in the channel to propel the stick of writing material, moving the propeller element out of the channel and back said predetermined distance, and then moving the propeller element again into said channel into its starting position at which it may act on another stick of writing material, moving another propeller element in the same manner as the first named propeller element, each of said propeller elements having the same starting position and being moved in said channel to propel a stick of writing material therein while the other propeller element is moved in the opposite direction without the channel, and clutching a stick of writing material feeding from said magazine in said channel at a point between the magazine and the starting position of the propeller elements just as each propeller element is reaching its starting position in its return movement for causing a spacing between adjacent sticks of writing material at the starting position of the propeller elements to allow the propeller element to enter the channel at the starting position.
